(57) **CLAIM**

The ornamental design for a wheel hub, as shown and described.

DESCRIPTION

FIG. 1 is a perspective view taken from the front, the top and the right of a wheel hub.

FIG. 2 is a perspective view taken from the rear, the bottom and the right of the wheel hub.

FIG. 3 is a top view of the wheel hub.

FIG. 4 is a bottom view of the wheel hub.

FIG. 5 is a front view of the wheel hub.

FIG. 6 is a rear view of the wheel hub.

FIG. 7 is a left side view of the wheel hub; and,

FIG. 8 is a right side view of the wheel hub.

1 Claim, 6 Drawing Sheets
